Fig. 2.

Fig. 3.

Fig. 4.

A detailed technical diagram of a mechanical assembly. It features a central circular component with a gear-like pattern, labeled with the number 84. Surrounding this central part are several other numbered components: 87 at the top left, 90 at the top left, 92 at the top center, 93 at the top right, 94 at the bottom right, 85 at the bottom left, 86 at the bottom center, 88 at the bottom left, and 89 at the middle left. The assembly is mounted on a rectangular base with two circular holes on the left side. A small gear is also visible on the right side of the base.

UNITED STATES PATENT OFFICE

RALPH E. KORTEPETER, OF BROOKLYN, NEW YORK, ASSIGNOR, BY MESNE ASSIGNMENTS, TO SPERRY GYROSCOPE COMPANY, INC., OF BROOKLYN, NEW YORK, A CORPORATION OF NEW YORK

BATTLE ORDER INSTRUMENT

Application filed December 29, 1921. Serial No. 525,594.

This invention relates to signalling devices, and more specifically to battle order instruments for use on warships for the transmission of orders or information from a fire control station to the vicinity of the guns or torpedoes for the benefit of the gun or torpedo crews.

The principal objects of the invention are to provide a device of this character which will possess a high degree of reliability; withstand rough usage and at the same time be of comparatively compact arrangement.

Other objects will appear in the following specification of the invention.

Referring to the drawings wherein I have shown what I now consider to be the preferred form of my invention:

Fig. 1 is a top view of the transmitter box with the cover and operating handles in position.

Fig. 2 is a sectional elevation of the transmitter taken on line 2—2 of Fig. 1.

Fig. 3 is a view of a switch looking in the direction of arrow A in Fig. 2.

Fig. 4 is a side elevation thereof.

Fig. 5 is a top view of a double throw electro-magnet.

Fig. 6 is a front elevation thereof.

Fig. 7 is an end view of a repeater motor with the end plate removed.

Fig. 8 is a sectional side elevation of said motor taken substantially on line 8—8 of Fig. 7.

Fig. 9 is a sectional side elevation taken on line 9—9 of Fig. 10 of a switch adapted to control said repeater motor.

Fig. 10 is a section of said switch taken on line 10—10 of Fig. 9.

Fig. 11 is a plan view of the receiving instrument with the cover removed.

Figs. 12 and 13 are wiring diagrams.

Referring to Figs. 1 and 2 of the drawings, the transmitter casing is shown at 1 with a cover 2 secured thereon by bolts 3.

Within the casing are the transmitting control elements adapted to be actuated by means of handles on the outside of the casing the said control elements may include switches 4, 5 having central spindles 6, 7 reaching without the top of the casing and having

handles 8, 9 fixed thereon. Said spindles are shown as projecting through bosses 10, and may be provided with packing 11 to prevent leakage of moisture or air along the spindle and into the casing. A grease cup 12 may be connected to the boss to supply lubricant to the packing to serve the double purpose of enhancing the water-proof or air-tight qualities of the packing and of lubricating the spindle in its bearing. In connection with one of the bearings I have shown washers 11^a pressed into position by a spring 11^b. The grease may then be pressed into the space in which the spring works to render the point more perfectly proof against leakage, so that in the event that a partial vacuum is created within the casing 1, the same may be maintained. An important reason for such tight joints is that when the apparatus is exposed to the weather or at least to damp atmosphere, and the heat caused by the electric coils within the casing causes the air therein to expand and force its way out through the joints, subsequent cooling of the apparatus would tend to be followed by suction of air into the casing, and the accompanying moisture would tend to cause corrosion or other bad effects upon the delicate metallic parts of the instrument. The switches are shown in greater detail in Figs. 9 and 10. The spindle 6 carries rigidly secured thereto insulation 13 to which are fixed two conductor rings 14, 15. Said rings are provided with extensions 16, 17 reaching over and forming arcs in the periphery of the central and raised portion of insulation 13. A plurality of brush contacts 18 secured to posts 19 engage said periphery and arcs, while brush contacts 20 secured to posts 21 engage rings 14 and 15. Posts 19, 21 are carried by member 22 mounted on a plate 23 which is in turn attached to the cover 2 by posts 23'. Rotation of spindle 6 will vary the combinations of contacts made between arcs 16, 17 and brushes 18. Posts 19, 21 may be of conducting material terminating in contact plugs 24, and may be supported near their lower ends by a member 25 which may also serve as a bearing for the lower end of spindle 6. Secured to 10a

the bottom of the casing 1 may be positioned the contact receptacles 25', so positioned as to register with the plugs 24 when the cover 2 of the casing is in position.

5 Switches 8, 9, 8' and 9' may be duplicates of each other.

Corresponding to each of these switches is a repeater motor 26 positioned in the casing 27 of the receiving instrument. The details 10 of this motor are more specifically set forth in the patents to Elmer A. Sperry, Jr. for Electrical transmission systems, No. 1,603,646, granted October 19, 1926, and for Repeater motors, No. 1,605,571, granted November 2, 15 1926, and need therefore only to be briefly described here. Referring to Figs. 7 and 8, the motor is shown as having five fixed field poles 28 provided with the usual windings 29, and a fixed armature coil 30 through which 20 projects a rotatable shaft 31 having pole pieces 32, 33 fixed thereto adjacent opposite ends of the armature magnet and projecting in opposite directions. The armature coil 25 may be constantly energized when the current is on so that the members 32, 33 will be north and south poles. Actuation of switch handle 8 will vary the combination of field poles energized and thus cause rotation of the armature shaft 31, as fully described in connection 30 with Fig. 13 of Patent No. 1,603,646, referred to above.

In order that the armature poles shall never be on dead center, so to speak, in the event that the transmitter handle is turned 180° 35 with the current off, in which case the motor would be held in such position and out of synchronism, I have shown means for throwing the armature out of its step positions whenever the current ceases to flow. Any 40 suitable means may be provided for this purpose. I have here shown the shaft 31 as provided with a star wheel 34 while a small armature 35 pivoted at 36 carries a pointed 45 detent 37 adapted to be pressed by a spring 38 into said star wheel. When the current is on the electro-magnetic power of shaft 31 will attract armature 35 and hold the detent out of contact with the star wheel, but when the current is turned off the spring 38 will 50 press the detent into the star wheel to turn shaft 31 slightly and hold it between operating step positions so that wherever the transmitter switch may be positioned when the current is again turned on, the combination of energized field poles 28 will exert a force upon the motor armature greater on one side of its rotating axis than on the other and the armature will thus be thrown into synchronism with the switch or transmitter.

55 The armature shaft 31 is shown as carrying a hub 39' with a skeleton 39 having an indicator card 40. The characters 41 on said card are adapted to move under a window represented by dotted lines 42 in the cover (not shown) of the casing 27. Said characters are

preferably translucent, so that a light in the rear of the card will render them luminous. The switch spindle 6 also carries an indicator card 43 visible through a window 44 in the cover 2.

70 The several transmitters 8, 9, 8' and 9' and their cards may, as we have seen, be similar in construction. The repeater motors 26, 26^a, 26^b, and 26^c and their cards may also be similar. The references on card 40 are shown as 75 comprising digits 0 to 9, and where a twenty step motor such as shown here is used, may be repeated to complete the circuit of the card. The card 40^c of motor 26^c, however, is shown as marked with 00, 05 and so on in increments 80 of five up to 95, while cards 40^a, 40^b may be marked from 0 to 19.

85 Mounted in the same plane as card 40^c is a sector 45 movable about an axis 46 coincident with the axis of the said card, and having a projecting lever arm 47 connected by a link 48 to the armature 49 of a magnet 50. The said armature is movable about a pivot 51 and may be attracted by either of poles 52, 53 of coils 54, 55. The rear part of the armature may be provided with flat portions 56 against which presses a flat spring 57 adapted to hold the armature in which ever 90 positions the magnets move it. The indications on the sector 45 may comprise a zero and the letters MIN; the latter being an 95 abbreviation of the word "minutes".

100 Corresponding to magnets 54, 55 is a switch 58 in the transmitting casing. The details 105 of this switch may be substantially the same as switches used elsewhere in the instrument and shown in Figs. 3 and 4 and which will hereinafter be described. The wiring diagram for the switches 8', 9' and motors 26^b, 26^c is the same as disclosed in the aforementioned Patent No. 1,603,646 and need not be shown here, while the wiring diagram for switch 58 and magnets 54, 55 is shown in Fig. 12 wherein it will be seen that the turning of switch 58 to close contacts 63-65 or 63-64 110 will complete a circuit through magnets 54 or 55.

115 The indications transmitted by switches 8', 9' and 58 to repeater motors 26^b and 26^c and magnets 52, 53 and readable through the window represented by dotted lines 59 represent the range of the target, and may be given either in terms of yards or angle of elevation to which the gun is to be raised. Presuming the range to be transmitted to be 7050 yards, switch 8' will be turned until 7 appears in the window 60, then switch 9' will be turned to present 05, and switch 58 which is also mechanically connected through link and levers 61 to sector 62 will be turned to present 0. These indications are reproduced through window 59 of the receiving instrument. If, on the other hand, it is desired to transmit to the gunner the elevation at which his gun should be set, switch 58 will be turned 125 130

in the opposite direction, i. e. to close contacts 63—64 (Fig. 12), thus rotating segment 45 to position the designation MIN in the window. The reading would then be 5 705 minutes or any other elevation desired.

Dials 40, 40^a may indicate deflection of the projectile in any suitable terms, such as minutes or other arbitrary units, and are, as we have seen, controlled from switches 8, 9.

10 In practice each gun to be controlled by the present system would be provided with one receiver and all of the receivers would be connected to the same transmitter. And where there are to be two transmitters, one 15 in the forward control station and one in after station, the receivers may be connected to both transmitters and a suitable switch provided for connecting the receivers to the desired station.

20 In the receiver I have shown an indicator card 66 having the designations "Forward", "Local", and "After" marked thereon. The card may be secured through an arm 67 to a magnetic device 68. Corresponding to this 25 in the transmitter is a card 66' bearing the references F, L and A. This card may be secured to a magnetic device 68'. This device which may be similar to device 68 is more clearly shown in Figs. 5 and 6. The 30 arms 67' which carries card 66' may be pivotally supported at 69 to a top plate 70; the latter being removed in Fig. 5 to reveal the other elements. Secured to and projecting downwardly from said arm is shown

35 a soft iron bar or armature 71 adapted to cooperate with the poles 72 of electro-magnets 73, 74. A flat spring 75 engaging the straight rear end 67^a of arm 67' is provided to hold the card 66' normally centralized so 40 that the L is visible through the window 76 (Fig. 1). When magnet 73 is energized the card will be moved to that side as shown in dotted lines 77 (Fig. 5) and the A will obviously appear in the window, and energization 45 of magnet 74 will render F visible. As in the case of the transmitter switches, the magnet device may be provided with contact plugs 78 adapted to engage receptacles 79 in casing 1 when the cover 2 is in place; the 50 device being attached at 80 to said cover 2. Associated with said magnets is a switch 82, the details of which are shown in Figs. 3 and 4. This switch may comprise a stem 84 on which the handle is mounted reaching 55 through cover 2 to the inner side thereof and carrying a drum 85 having a contact 86 adapted to cooperate with either of contacts 87, 88 when rotated in one direction or the other. Also fixed on said spindle is a wheel 60 89 having three notches 90 cut therein and engaged by a projection 92 on a spring pressed lever 93. The projection will thus serve to hold the switch in the position to which it has been turned. The switch is secured by screws 94 to a boss 95' on the inside

of cover 2. The switch handle 95^a may be provided with a projection 95^b (Fig. 2) adapted to engage stops 96 on the boss 96' through which spindle 84 passes, to limit the extent that the switch may be turned. 70

In Fig. 13 I have shown a wiring diagram which may be employed where there are two control stations. The switch 81 may be located near the device 68 at the gun; while device 68' and switch 82 are in the forward control instrument and device 68'' and switch 83 are in the after control station. The switch 81 may be normally in the position shown; the forward station being in control and the after station being cut out. If the officer at the forward station is to control the firing he communicates this information to the gun by turning switch 82 to close contacts 86—87. This will complete a circuit from the positive side of the feed lines 97, through 85 switch 81, line 98, contacts 86, 87, line 99, coil 73, lines 100, 101, coil 102, and line 103 to the negative side of the feed. Thus coils 73 and 102 will be energized resulting in positioning the designation "For'd" in 90 the window 104 of the receiver, and "F" in window 76 of the transmitter. The positioning of the indications in the transmitter window will indicate to the control officer that the apparatus is functioning properly. 95

If it is intended that the gun crew shall receive orders from the after station the officer at the forward station will turn switch 82 to close contacts 86—88. The word "After" will then appear in widow 104 and the letter 100 "A" in widow 76. The gun crew, will, upon receipt of this order throw switch 81 to connect the receiver with the after transmitter. All orders thereafter received will come from that station. It will, of course, be understood 105 that the throwing of switch 81 will connect all elements of the receiving instrument with the forward or after control station as the case may be. The designation "Local" on the card 66 of the receiver and the "L" on 110 card 66' of the transmitter serve to instruct the gun crew to assume local control in operating the gun. This position as we have seen will be assumed whenever there is no current flowing. Thus, should the connection with the control station be shot away or otherwise destroyed the gun crew would be automatically instructed to assume local control, and the officer stationed at the gun in charge of the gun crew would control according to his 120 own judgment. 115

In Fig. 1 I have shown several switches 82' and corresponding indicators 76', similar to switch 82 and indicator 76. Each of these 125 may be connected to a separate receiver so that any gun or group of guns may be instructed to receive orders from the after station or to assume local control while others are retained in control of the forward station.

Positioned in the lower right hand corner 130

of the receiver I have shown an indicator card 105 bearing designations designed to instruct the gun crew, when in one position, to follow the pointer in training the gun, in which case the gun will be trained to coincide with a pointer controlled from a distance and kept pointing in the direction of the target. The latter instrument forms no part of the present invention and is therefore not shown here. In another position the card will instruct the gun crew that the gun is to be fired by the director firing system. And when in the central position with the word "Pointer" in the window 106 the gunners will be instructed to do all aiming through the regular sighting elements. The construction of magnets 107 with the card 105 may be the same as disclosed in Figs. 5 and 6. The switch 108 in the transmitter which controls these magnets may in turn be the same as that disclosed in Figs. 3 and 4. The wiring diagram shown in Fig. 12 may also serve in this instance. The indicator card 105' in the transmitter, however, is here shown as connected directly to the spindle 109 of switch 108 at 110 and is visible through window 111.

At 112 and 113 in the receiver I have shown additional indicator cards actuated by electro-magnets 114, 115. These magnets and cards are controlled by switches 116, 117 in the transmitter. These devices too may be the same as disclosed in Figs. 3 to 6, and the cards 112', 113', visible through windows 118, 119 in the transmitter may be secured to the switch spindles in the same manner in which card 105' is secured to spindle 109. The card 112 is designed to instruct the gun crew as to the type of shell to be used, while card 113 instructs the gunners to fire or to cease firing, and in its centralized position indicates that the circuit is broken. If, during operations, neither the order to fire nor to cease firing is visible through window 119', the information that the circuit is broken will appear. The gunners will then, where two stations are provided throw switch 81 (Fig. 13) to pick up the after control station. If but one station is provided or the circuit remains broken when the after station is thrown in, the gun crew will assume full control in firing the gun as in the case where the local control order is given.

Within the transmitter casing 1 and the receiver casing 27 I may place one or more lamps 120, 121 as many be necessary to illuminate the reference characters at all of the windows. Any suitable method may be employed for causing reflection of the light emanating from the lamps to said windows, such for instance as painting the interior walls of the casings with white or other light reflecting coatings.

In accordance with the provisions of the patent statutes, I have herein described the principle of operation of my invention, to-

gether with the apparatus, which I now consider to represent the best embodiment thereof, but I desire to have it understood that the apparatus shown is only illustrative and that the invention can be carried out by other means. Also, while it is designed to use the various features and elements in the combination and relations described, some of these may be altered and others omitted without interfering with the more general results outlined, and the invention extends to such use.

Having described my invention what I claim and desire to secure by Letters Patent is:

1. In an indicating instrument, a pair of circular indicating cards positioned in a common plane substantially tangential to each other externally so that contiguous indications together indicate a single quantity, one of said cards comprising a ring, a third card positioned within said ring so as to read conjointly with said first mentioned cards, and means for actuating each of said cards.

2. In an indicating apparatus, a casing having a window therein, a plurality of rotatable indicating disks movable adjacent said window for reading therethrough, said discs being so positioned that contiguous indications on adjacent discs form a single quantity, one of said disks having a depressed central portion, and an indicating card positioned within said central portion also readable through said window conjointly with said disks.

In testimony whereof I have affixed my signature.

RALPH E. KORTEPETER.
